CLAIM

The ornamental design for an electronic copying machine, substantially as shown.

DESCRIPTION

FIG. 1 is a front, top and right side perspective view of an electronic copying machine showing our new design;

FIG. 2 is a front elevational view thereof;

FIG. 3 is a right side elevational view thereof;

FIG. 4 is a top plan view thereof;

FIG. 5 is a rear elevational view thereof;

FIG. 6 is a left side elevational view thereof;

FIG. 7 is a perspective view with the cover in an open position; and

FIG. 8 is an enlarged top plan view of the operation section of the machine.

FIG. 1
